UNITED STATES PATENT OFFICE.

ALEXIS KONSHIN, OF YOKOHAMA, JAPAN, ASSIGNOR OF ONE-HALF TO JOHN GADSBY,
OF TOKYO, JAPAN.

WINDPROOF MATCH BOX.

Application filed January 6, 1922. Serial No. 527,473.

To all whom it may concern:

Be it known that I, ALEXIS KONSHIN, citizen of Russia, residing at 46-A Yamate-cho, Yokohama city, Empire of Japan, have invented certain new and useful Improvements in Windproof Match Boxes, of which the following is a specification.

Explanation of the drawings.

10 Figure 1 is a plan view of a wind proof match box made in accordance with this invention shewing the inner receptacle partly withdrawn, and Figure 2 is a longitudinal section of the same on the line X—Y of 15 Figure 1.

Referring to the drawings, A shews an outer casing of which the upper half is disclosed at G, the remaining portion being closed at E and adapted to provide a face 20 to which any substance for match lighting, such as a firing preparation, may be applied.

One of the ends adjacent to this disclosed portion G of the top is covered by a member H in the same manner as in the outer 25 portion of the outer casing, while the opposite end adjacent to the igniting portion of the top member remains uncovered so that the inner receptacle can freely be drawn out or pushed in. In a word, the outer casing 30 comprises one complete bottom member, two complete side members, one complete end member and one top member corresponding in size to one half of that of the bottom member, said members being formed in a 35 parallelopiped.

The inner receptacle B has also the shape of a parallelopiped having its bottom, two sides and two ends completely closed but with its top covered only with respect to the 40 portion E which corresponds to the disclosed top portion G of the outer casing. The remainder of the top area which lies under the igniting portion of the outer casing remains uncovered.

45 On the visible end of the inner receptacle is provided a tab D at a suitable point such as the end of the bottom member, thereby facilitating the withdrawal of the receptacle.

The match box may be constructed of sheet metal for both the outer covering and 50 the inner receptacle, or the outer casing may be made of sheet metal and the inner receptacle of thin pieces of wood connected by a coating of paper in the usual manner.

However the usual method of constructing 55 match boxes out of paper and thin pieces of wood, may be resorted to with success if the principles of this invention are carried out without fail. It is understood that any material suitable for the manufacture of match 60 boxes may be employed.

In use, a match stock C is removed from the inner receptacle B and lighted by being applied to the portion B of the outer casing. As soon as the head of the match stick is ignited, it should be placed in the space G without loss of time. With the arranged 65 nited, it should be placed in the space G caused by draughts or winds which must have been experienced in the use of ordinary 70 match boxes and also the consequent waste of matches, can be prevented.

I claim—

A wind-proof match box including an outer casing of the usual parallelopiped type having one of its ends entirely closed by an end wall and its top partially removed, an abrasive substance arranged on the outer surface of the remaining portion of the top, and an inner receptacle for matches having its top 75 partially covered so as to furnish a cover corresponding in position to the uncovered portion of the outer casing, when the inner receptacle is placed in the usual way within the outer casing, the match box being adapted 80 to provide a space inside the outer casing when the inner receptacle is partially withdrawn to receive the lighted end of an ignited match.

In testimony whereof I have affixed my 85 signature in presence of two witnesses.

ALEXIS KONSHIN.
